(57) CLAIM

I claim the ornamental designs for the scrambler jacket, as shown and described.

DESCRIPTION

FIG. 1 is a side perspective view of the scrambler jacket of my new design;

FIG. 2 is a front view of the scrambler jacket;

FIG. 3 is another front view of the scrambler jacket, showing the center zipper flap unzipped, in an opened position;

FIG. 4 is another front view of the scrambler jacket, showing the two center openings completely unzipped;

FIG. 5 is a back view of the scrambler jacket;

FIG. 6 is a partial front view of the scrambler jacket, showing the collar unsnapped, in an opened position; and,

FIG. 7 is another partial view of the collar of the scrambler jacket, showing the collar completely fastened in a closed position, and the left pocket zipped in a closed position.
